Filed Apr. 27, 1962, Ser. No. 190,639
9 Claims. (Cl. 51—337)

This invention relates to a flap-type abrasive wheel wherein an annular array of flexible abrasive leaves is mounted on a rotary hub structure with individual leaves extending radially therefrom for abrasive action on a workpiece. The leaves are commonly made of cloth with hard sharp particles of abrasive material such as aluminum oxide or silicone carbide bonded to one face of the cloth.

The desired function of such a wheel is to provide two kinds of abrasive action on a workpiece. One abrasive action is a slapping action of initial contact of each successive leaf against the workpiece and the other abrasive action is a following wiping action as the leaf moves beyond the point of initial contact. Each leaf working alone is too flexible for effective abrasion by its wiping action but the successive leaves are spaced close enough to each other to pack together at the wiping zone, each wiping leaf being reinforced and backed by a number of following leaves.

Unfortunately each successive leaf not only slaps against the workpiece but also slaps against the cloth back of the immediately preceding leaf and then each successive leaf not only wipes against the workpiece but also rubs against the cloth back of the immediately preceding leaf, the rubbing action being severe because of the pressure exerted by the closely crowded leaves on each other. Consequently the leaves abrade each other to shorten the service life of the abrasive wheel, as may be readily appreciated by examining the lacerated backs of the leaves at their outer ends after a short initial period of operation of a new abrasive wheel.

For a relatively fast abrasive action on a workpiece, as many leaves as possible are commonly used in an annular array of leaves with no spacing between the anchored ends of the individual leaves to cause the maximum number of leaves to pack together for creating relatively high abrasive pressure against the workpiece. Unfortunately, however, using the maximum number of leaves in the array also results in relatively high pressure of leaf against leaf, to result in fast wear on the backs of the leaves.

One solution heretofore advanced for this problem is to interpose smooth spacer leaves between the successive abrasive leaves, the annular array consisting of abrasive leaves and alternate smooth paper leaves. Counting the spacer leaves along with the abrasive leaves, this solution employs the maximum number of leaves to achieve relatively high wiping pressure against a workpiece and the solution does protect the cloth backs of the abrasive leaves against laceration. An economical disadvantage of the solution, however, is that the abrasive potential of the array of leaves, i.e. the total area of the abrasive leaves available for processing workpieces, is reduced by half.

The present invention eliminates the abrasive wear on the cloth backs of the abrasive leaves without incurring this economic disadvantage. This object is accomplished by the simple expedient of arranging the abrasive leaves of the array in successive pairs with the abrasive faces of the two leaves of each pair facing each other. Thus the annular array of abrasive leaves comprises two sets of alternate leaves facing in opposite rotary directions.

An unexpected advantage of this solution to the problem is that abrasive wear among the leaves of the array is reduced in two ways. In the first place the abrasive action of each leaf is directed against the abrasive face of the next leaf and since the two opposed surfaces are

2

of equal hardness and abrasive resistance, relatively little wear is created. In the second place, the abrasive particles of the confronting abrasive faces of the pairs of leaves interlock to reduce slippage between the abrasive faces.

For those operations where relatively high abrasive pressure against a workpiece is desirable, the new arrangement has a further advantage in increasing the pressure. The abrasive pressure is increased because the interlocking of the abrasive particles of the confronting abrasive faces of each pair of leaves has the effect of increasing the resistance to flexure of the pair.

Since all the leaves of the annular array of pairs of leaves are functional abrasive leaves, the maximum abrasive potential is afforded, i.e. the maximum total of abrasive leaf area is available for processing workpieces. It is a simple matter to reverse the direction of rotation of the hub structure to change from abrasive action by one of the sets of leaves facing in one rotary direction to abrasive action by the other set facing in the opposite rotary direction.

An important feature of one form of the invention is that the two sets of abrasive leaves are of different grades, one set having relatively fine abrasive particles and the other set having relatively coarse abrasive particles. After initially abrading a workpiece with the relatively coarse abrasive particles, it is merely necessary to reverse the direction of rotation of the abrasive wheel to switch to a finishing abrasive operation with finer abrasive particles. Thus the invention provides a dual purpose abrasive wheel having the versatility of a set of two different abrasive wheels and the abrasive potential of the dual purpose wheel is equal to the combined abrasive potential of two separate abrasive wheels that incorporate alternate non-abrasive spacer leaves.

A further feature of the invention is the concept of spacing apart the anchored or root portions of the abrasive leaves at the circumference of the hub structure to modify the abrasive action of the wheel for operations where a "softer" or more yielding abrasive action is desirable. When a workpiece is inserted into the outside circumference of a flap-type abrasive wheel, the leaves are deflected or inclined backwards with respect to the direction of rotation by contact with the workpiece. There is a limit to which the leaves can be inclined backward, however, the limit being at what may be termed the "solid" diameter or radius at which no voids remain between the inclined closely packed leaves. In a conventional flap-type abrasive wheel, i.e. an abrasive wheel having the maximum number of leaves, for example a wheel in which the radial dimension of the hub structure relative to the axis of rotation is 2 3/4 inches and the abrasive leaves extend radially outward five inches from the axis, the solid radius of the wheel is found to be approximately 4 1/2 inches, and the wheel may be said to have a yielding depth of 1/2 inch. If a flat workpiece held substantially tangentially of the abrasive wheel is inserted 1/4 inch into the rotating annular array, only 1/4 inch remains of the yielding depth and, with the workpiece only 1/4 inch from the solid radius, the yielding resistance of the abrasive wheel is relatively high to result in correspondingly relatively high abrasive pressure against the workpiece. It has also been found that providing the abrasive wheel with the maximum number of abrasive leaves results in an excessive number of leaves packing together in the region of contact with the workpiece, the consequent mutual reinforcement of the leaves tending to create relatively high abrasive pressure against the workpiece. It has been further found that excessive packing together of the leaves practically eliminates freedom for slapping action of the individual leaves against the workpiece.

Reducing the number of abrasive leaves to half by spacing the root portions of the leaves apart by the thickness

of one leaf not only reduces the solid radius to increase the yielding depth of the abrasive wheel to approximately $1\frac{1}{4}$ inches, but also reduces the number of leaves that pack together in mutual reinforcement in the region of contact with the workpiece. Consequently a workpiece lying $\frac{1}{4}$ inch inside the outer circumference of the annular array of leaves is subjected to a lighter and more yielding abrasive action. In addition, the individual leaves are free for the desired slapping action against the workpiece.

If the number of leaves is reduced to $\frac{1}{3}$ of the maximum number of leaves by spacing the root portions of the leaves apart by the thickness of two leaves, the result is further reduction in the severity of the abrasive action. The yielding depth of the abrasive wheel is increased to more than $1\frac{1}{2}$ inches and only a relatively few leaves pack together to create abrasive pressure in the region of contact with the workpiece.

The features and advantages of the invention may be understood by reference to the following detailed description and the accompanying drawing.

In the drawing, which is to be regarded as merely illustrative:

FIG. 1 is a side elevation of a selected embodiment of the invention;

FIG. 2 is a diametrical section taken along the line 2-2 of FIG. 1;

FIG. 3 is a fragmentary portion of FIG. 1 greatly enlarged to show how the abrasive leaves are arranged in pairs with mutually opposed abrasive faces;

FIG. 4 is a diagrammatic side elevational view showing how the leaves flex and crowd together in the region of contact with a flat surface of a workpiece;

FIG. 5 is a fragment of FIG. 4 greatly enlarged;

FIG. 6 is a fragmentary side elevational view showing how inner end portions of the leaves may be folded to serve as spacers to result in the root portions of the leaves being spaced apart by the thickness of one leaf;

FIG. 7 is a similar view showing spacers interposed between the successive leaves to space the leaves apart by the thickness of two leaves;

FIG. 8 is a similar view showing how spacers may be employed only between the successive pairs of leaves, there being no spacer between the two leaves of each pair; and

FIG. 9 is a similar view showing how spacers may be interposed only between the confronting abrasive faces of each pair of leaves, there being no spacers between the successive pairs of leaves, i.e. no spacers between the confronting smooth back faces of the abrasive leaves.

FIGS. 1 and 2 illustrating the invention show a flap-type abrasive wheel of a well-known construction wherein an annular array or assembly, generally designated 20, of individual abrasive leaves 22 is mounted on a hub structure, generally designated 24. As shown in FIG. 2, the hub structure 24 includes a spindle 25 for rotary actuation by a suitable motor, the spindle having a screw thread 28. Two opposite side plates 30 are slidably mounted on the spindle 25 to clamp the assembly of abrasive leaves 22 from opposite sides, the two side plates being confined between a pair of nuts 32 and 33. As further shown in FIG. 2, the annular assembly 20 of abrasive leaves is formed with two concentric circular grooves 35 on the opposite sides respectively of the assembly and the two side plates 30 are formed with inwardly turned circular flanges 36 which seat into the two grooves for effective anchorage of the abrasive leaves against centrifugal force.

The abrasive leaves 22 are of a well-known construction comprising pieces of cloth with abrasive particles bonded on one face of the cloth, the opposite face of the cloth being smooth. In a conventional abrasive wheel of this character, the abrasive faces of the abrasive leaves all face in the same direction of rotation. In the present invention, however, the alternate abrasive leaves 22 face in opposite directions. Thus as indicated in FIG. 3 the annular array 20 comprises successive pairs of leaves with

their abrasive faces turned toward each other, each pair comprising an abrasive leaf 22a and an abrasive leaf 22b. The abrasive leaf 22a of each pair has an abrasive face 38 and a smooth back or face 40 and the abrasive leaf 22b of each pair has an abrasive face 42 and a smooth back or face 44. While the abrasive faces 38 and 42 of the confronting abrasive leaves may be of the same grade, in this instance the abrasive faces 38 of the leaves 22a comprise abrasive particles of relatively fine size and the abrasive faces 42 of the leaves 22b comprise coarser abrasive particles.

FIG. 4 shows how the abrasive leaves are flexed by contact with a workpiece having a flat surface, the flat surface being indicated by the straight line 45. FIG. 5 is an enlarged detail of the same view. It may be readily appreciated that the abrasive particles of the confronting abrasive faces 38 and 42 of the pairs of leaves 22a and 22b tend to interlock to resist slippage between the two abrasive faces. Slippage does occur, however, to expose tip portions of the abrasive leaves 22a for abrasive action on the workpiece but, nevertheless, the slippage is reduced in magnitude and is materially less than would occur between smooth surfaces. Thus there is less slippage between the confronting abrasive faces 38 and 42 inside each pair of leaves 22a and 22b than occurs between the confronting smooth back faces 40 and 44 between the successive pairs of leaves. In effect the resistance to slippage between the two confronting abrasive faces of a pair of leaves 22a and 22b causes the two leaves of the pair to reinforce each other against flexure by the workpiece. Thus the new arrangement of oppositely facing leaves has a stiffening effect to increase the pressure of the abrasive leaves against the surface of the workpiece.

It is further apparent that although all of the abrasive leaves 22a and 22b slip and rub on each other in a cyclic manner in the course of each rotation of the abrasive wheel, nevertheless actual wear of leaf on leaf is very slight because all of the mutually rubbing surfaces are of equal hardness. Since the confronting abrasive surfaces are of equal hardness, they do not create any significant wear on each other even though they are abrasive. Since the confronting smooth cloth back faces 40 and 44 are not only of equal hardness but also are non-abrasive, no significant wear occurs on the backs of the abrasive leaves. In fact after long usage, the backs of the abrasive leaves show no indication of wear whereas in a conventional abrasive wheel where all of the abrasive surfaces face in the same direction of rotation, substantial laceration of the cloth backs of the leaves may be observed after only a short period of service.

It is apparent that the operation of the abrasive wheel may be converted from abrasion with relatively coarse particles to abrasion with relatively fine particles or vice-versa, by merely reversing the direction of rotation of the wheel. Thus if the abrasive wheel is driven by a reversible motor it is merely necessary to reverse the motor to change from abrasion with one grade of particles to abrasion with a different grade of particles. If the motor is not reversible, the position of the abrasive wheel may be reversed on the spindle 25 to switch from one operation to the other whenever desired.

As heretofore stated, the maximum number of abrasive leaves is employed in a conventional flap-type abrasive wheel. In the first embodiment of the invention shown in FIGS. 1-5, the maximum number of abrasive leaves is also employed, there being no spacing between the anchored portions of the successive leaves 22, the leaves being packed snugly together in the region of the circumference of the hub structure 24. As heretofore stated, however, the use of the maximum number of abrasive leaves results in the annular array of leaves having a relatively shallow yielding depth measured to the solid diameter of the array and such an abrasive wheel exerts relatively heavy abrasive pressure on a workpiece. In addition the abrasive pressure rises ex-

ponentially if the depth of penetration of the workpiece into the outer circumference of the annular array is increased. Thus the depth of penetration is critical with respect to control of the abrasive pressure on the workpiece.

Also, as heretofore stated, the yielding depth of the abrasive wheel may be increased, the abrasive pressure against the workpieces decreased, and the depth of penetration made less critical by reducing the number of abrasive leaves in the annular array. FIG. 6, for example, shows how inner end portions 46 of the abrasive leaves may be folded to serve as spacers between the successive leaves at the anchored ends of the leaves in the region of the circumference of the hub structure of the abrasive wheel. Thus the successive oppositely facing abrasive leaves 52a and 52b of FIG. 6 are spaced apart by the thickness of a single leaf and the total number of leaves is reduced by half. It has been found that the construction indicated in FIG. 6 reduces the number of leaves that are crowded together in mutual support in the region of contact with the workpiece, this factor having the effect of reducing the abrasive pressure against the workpiece. It has also been found that the construction shown in FIG. 6 provides greater freedom for the desired slapping action by the individual leaves in their initial contacts with a workpiece.

FIG. 7 shows how the number of abrasive leaves may be reduced even further by employing spacers 54 between the successive leaves of an array, the leaves comprising successive pairs of leaves 62a and 62b with confronting abrasive faces. In this instance the spacers 54 are of approximately twice the thickness of an abrasive leaf, the array having only one-third of the maximum leaves employed in a conventional abrasive wheel.

FIG. 8 illustrates another practice of the invention in which spacers 64 are employed only between the successive pairs of leaves, not between the leaves of each pair. An advantage of this arrangement is that it not only increases the yielding depth of the abrasive wheel but also has a selective effect in tending to increase the freedom for slippage between the confronting smooth back faces of the leaves.

FIG. 9 illustrates another practice of the invention in which spacers 74 are employed only between the two leaves of each pair, there being no spacing between the successive pairs. Thus the spacers 74 space apart the abrasive faces of each pair of leaves, there being no spacing between the exposed smooth back faces of the abrasive leaves. This construction may be used where it is desirable to reduce to some degree the interlocking action between the confronting abrasive faces. Thus if the resistance to slippage between the mutually opposed abrasive faces is found to be excessive, the spacers 74 may be used to give the opposed abrasive faces more freedom for slippage.

My description in specific detail of the selected embodiments of the invention will suggest various changes, substitutions and other departures from my invention within the spirit and scope of the appended claims.

I claim:

1. In an abrasive device, the combination of:

a rotary hub structure;

an annular array of leaves free at one end and anchored at the other end to the hub structure to act on a workpiece by a slapping action and a wiping action, each of said leaves having a non-abrasive face on one side and an abrasive face on the other side covered with abrasive particles, said leaves of the array being arranged in successive pairs with the abrasive faces of the leaves facing in a direction of rotation with the leaves of each pair confronting each other for abrasive action at the free end of the leaves in both of the opposite directions of rotation of the hub structure and to resist relative sliding action between the leaves of each pair.

2. A combination as set forth in claim 1 in which each of said pairs of leaves comprises a leaf with relatively fine abrasive particles and a leaf with relatively coarse abrasive particles, all of the leaves with relatively fine abrasive particles facing in one direction of rotation of the hub structure whereby the hub structure may be rotated in one direction to apply the relatively fine abrasive particles to a workpiece and may be rotated in the opposite direction to apply the relatively coarse abrasive particles to a workpiece.

3. A combination as set forth in claim 2 wherein the anchored ends of the leaves are spaced by a distance of at least one thickness of the leaf to soften the abrasive action of the leaves against the workpiece.

4. A combination as set forth in claim 1 in which the anchored ends of said leaves are spaced apart by a distance on the order of one to two thicknesses of a leaf to lessen the solid diameter of the array and soften the abrasive action of the array against the workpiece.

5. In an abrasive device, the combination of:

a rotary hub structure;
an annular array of leaves free at one end and anchored at the other end to the hub structure to act on a workpiece by a slapping action and a wiping action, each of said leaves having a non-abrasive face on one side and an abrasive face on the other side covered with abrasive particles, said leaves of the array being arranged in successive pairs with the abrasive faces of the leaves of each pair confronting each other for abrasive action at the free ends of the leaves in both of the opposite directions of rotation of the hub structure and to resist relative sliding action between the leaves of each pair, the anchored ends of the leaves with confronting non-abrasive faces being contiguous, the anchored ends of the two leaves of each pair of leaves with confronting abrasive faces being spaced apart by at least approximately the thickness of one leaf.

6. A combination as set forth in claim 5 in which each of said pairs of leaves comprises a leaf with relatively fine abrasive particles and a leaf with relatively coarse abrasive particles, all of the leaves with relatively fine abrasive particles facing in one direction of rotation of the hub structure whereby the hub structure may be rotated in one direction to apply the relatively fine abrasive particles to a workpiece and may be rotated in the opposite direction to apply the relatively coarse abrasive particles to a workpiece.

7. In an abrasive device, the combination of:

a rotary hub structure;
an annular array of leaves free at one end and anchored at the other end to the hub structure to act on a workpiece by a slapping action and a wiping action, each of said leaves having a non-abrasive face on one side and an abrasive face on the other side covered with abrasive particles, said leaves of the array being arranged in successive pairs with the abrasive faces of the leaves of each pair confronting each other for abrasive action at the free ends of the leaves in both of the opposite directions of rotation of the hub structure and to resist relative sliding action between the leaves of each pair, the anchored ends of the confronting leaves of each pair being contiguous, the successive pairs of leaves at their anchored ends being spaced apart by at least approximately the thickness of one leaf.

8. A combination as set forth in claim 7 in which each of said pairs of leaves comprises a leaf with relatively fine abrasive particles and a leaf with relatively coarse abrasive particles, all of the leaves with relatively fine abrasive particles facing in one direction of rotation of the hub structure whereby the hub structure may be rotated in one direction to apply the relatively fine abrasive particles to a workpiece and may be rotated in the opposite direction to apply the relatively coarse abrasive particles to a workpiece.

posite direction to apply the relatively coarse abrasive particles to a workpiece.

9. The combination set forth in claim 7 wherein a spacer is disposed between the leaves of each pair,
